UNITED STATES PATENT OFFICE.

LAZAR SELIBER, OF NEW YORK, N. Y.

DESIGN FOR A WRIST WATCH OR ARTICLE OF SIMILAR NATURE.

Application filed February 12, 1926. Serial No. 16,501. Term of patent 7 years.

To all whom it may concern:

Be it known that I, LAZAR SELIBER, a citizen of the United States, residing at New York city, in the county of Bronx and State of New York, have invented a new, original, and ornamental Design for a Wrist Watch or Article of Similar Nature, of which the following is a specification, reference being had to the accompanying drawing, forming a part thereof.

In the drawings:

Fig. 2 is a side elevational view thereof.

I claim:

The ornamental design for a wrist watch or article of similar nature, as shown.

In testimony whereof I affix my signature.

LAZAR SELIBER.
